MEMBRANE UNIT STRUCTURE

Carl S. Strom, Chicago, Ill., assignor to United States Gypsum Company, Chicago, Ill., a corporation of Illinois

Application May 14, 1932, Serial No. 611,333

15 Claims. (Cl. 189—88)

This invention relates to building structures and means therefor, and more particularly relates to the construction of interior building surfaces where, for example, it is desired to provide sound insulation and/or fire protection.

In the construction of building interiors, such rooms, halls, auditoriums, industrial and commercial quarters, passageways, or any other building interiors where, by reason of commotion, 10 mechanical noises, talking, or the like, disagreeable acoustical confusion or distortion results, and it is desired to obtain acoustical insulation or correction, it becomes highly desirable to provide means associated with the building surface 15 to secure the necessary acoustical control.

To this end various expedients have been suggested, among which it has long been recognized that a perforated metallic membrane, backed by sound-absorbing material, secured adjacent a 20 building surface, provides a sound insulating medium having signal advantages. In order to facilitate erection of a metallic membrane surface, however, it has been suggested to divide the metallic membrane into a plurality of membrane 25 units, adapted to be connected in place on suitable support means adjacent a building surface. Difficulty has, however, been encountered in installing these membrane units, both because of the labor attendant upon erection and because 30 of the poor quality of surface resulting after erection. Means which have been suggested heretofore for securing the membranes in place have generally called for undue expenditure of time and effort with the resultant high installation cost and, then, after the membranes had 35 been placed, they would not be aligned in a substantially uniform plane, whereby objectionable high lights and uneven light reflection would be apparent, whereby the aesthetic appeal of the 40 surface was destroyed.

Moreover, where the membranes were provided with perforations to facilitate the travel of sound waves therethrough, to be absorbed by the absorbent material behind the membranes, the absorbent material was generally supported directly by the membranes. Much difficulty was, therefore, encountered when it became desirable to wash the surface, since the liquid washing medium would penetrate the absorbent material and then drip downwardly to again soil and disfigure the exposed surface of the membrane.

It is, therefore, an object of the present invention to provide a membranous building surface which is inexpensive and simple to install, which, 55 after installation, will present a uniform surface

substantially without high lights or uneven light reflection, and which lends itself readily to effective decoration and washing.

It is also an object of the invention to provide a sound insulative building surface which is fire-proof, and which is effective to render the desired 5 acoustical control.

Another object of the invention is to provide membrane units for building structures provided with improved means for attaching the same in 10 erection, and which will reduce the labor of installation to a minimum.

A further object of the invention is to provide improved clips for securing membrane units in 15 building construction; also to improve building construction in other respects hereinafter specified and claimed.

Reference is to be had to the accompanying drawing, forming a part of this specification in which

Fig. 1 is a perspective view of one of my improved membrane units;

Figure 2 is a fragmentary, sectional elevation through an acoustical ceiling construction, embodying the principles of my invention;

Figure 3 is a fragmentary perspective of a perforated metallic membrane embodying my invention, provided with a modified form of clip; and

Figure 4 is a fragmentary, sectional perspective of one of my membrane units provided with a clip adapted to engage with an improved form of support rail or runner.

In the co-pending application of James S. Offutt and Carl S. Strom, Serial No. 574,524, filed November 12, 1931, entitled "Acoustical ceiling construction", there are shown and described in considerable detail improvements in acoustical constructions of a type herein contemplated. My present disclosure, therefore, contemplates certain additional means to facilitate erection of this type of construction.

Membranes 10, which may be made of sheet iron, sheet aluminum, or other metallic or non-metallic sheet material, are preferably provided with substantially perpendicular, peripheral flanges 11, provided with an intermediate section 12, extending upwardly at an obtuse angle to the membranes 10, sections 11 and 12 thus forming beveled sides on the membranes. A plurality of off-sets 13 are preferably provided in the flanges 11, said off-sets being adapted to receive the substantially U-shaped portion 15 of clips adapted for attaching the membrane units in building construction. Off-sets 13 preferably

comprise bands severed from the flanges 11 and bridging the slots thus formed in off-set relationship to the flanges. I have found it desirable to provide knock-outs or slots 16 in off-sets 13 to receive the lower legs of the clips. Perforations 18 are preferably provided in the membranes 10 so that after said membranes have been installed sound waves will be permitted to travel therethrough to be absorbed by sound absorbent material 19 supported in spaced relationship between membranes 10 and building surface 20.

As shown in Figures 1 and 2, the clips for securing membranes 10 to flanges 22 of support runners 23, comprise a base 25 having a depending flange 26 at one end adapted to contact membranes 10 and space base 25 therefrom. U-shaped portion 15 at the other end of base 25 is adapted to engage with an off-set 13 of a membrane 10. Portion 15 is provided with leg 27, bent somewhat downwardly to facilitate engaging with an off-set 13 and to prevent accidental displacement of the clip. Resilient tongue 29, provided with shoulder 30, which is secured by means of spot welding or the like to base 25, engages over flanges 22 of a runner 23. Loop 31 extends upwardly from shoulder 30 and then downwardly to abut base 25, said loop 31 improving the resiliency and contact bearing of tongue 29 with a flange 22.

In a ceiling, the runners 23 are preferably suspended from the building surface 20 by means of quick-gripping, L-shaped hanger brackets 33, having depending legs 34, provided at their lower ends with U-shaped clamps 35 adapted to grip upper flanges 36 of runners 23. Toggle bolts, or the like, 37 secure hangers 33 to the surface 20. To insure positive gripping of clamps 35, a rod or bar 38, having hooks 39, is preferably provided to extend between adjacent hangers 33 to engage legs 34 thereof. Rod 38 also provides support for the sound absorbent material 19, which is preferably of a porous, fibrous nature, such as a pad of mineral wool, hair cloth or vegetable fiber. This construction, it is evident, may be installed either in an old or new building with equally good results.

The modified form of clip illustrated in Figure 3, similarly to the form of clip heretofore described, preferably comprises a U-shaped portion 15 adapted to engage with an off-set 13 in the side of a membrane 10, lower leg 41 of the portion 15 preferably extending through slot 16 in said off-set 13. Leg 41 is preferably bent downwardly to contact membrane 10 and serves to retain the clip in position so that upper leg 42 of portion 15, which comprises a base extending substantially back over membrane 10, will be retained substantially parallel to the membrane in order to facilitate engagement of integral, return bent tongue 43 with a flange 22 of a runner 23.

In order to provide means for snapping the membranes 10 up into place against a supporting member, I provide a modified form of clip, similar to the clip illustrated in Figure 3, but preferably having a somewhat shorter base 44 and an upstanding resilient tongue 45. As an example of the type of support rail with which this form of clip is adapted to engage, I have shown in Figure 4 an improved rail which I designed especially for this type of construction. The rail preferably comprises a substantially triangular body portion, having a base 47, sides 48, and outwardly extending flanges 49 adapted to be engaged by clamps 35 of hangers 33. Tongue

45, which extends upwardly at about the same angle as a side 48 of the rail, it is apparent, will resiliently snap into engagement with said side 48 when the membrane unit is pushed up against the rail.

My construction provides for positive frictional engagement of the supports to effectively maintain the membranes in a single plane and once the membranes are in place they will not be accidentally displaced. The sound absorbent material 19 is spaced away from the membranes 10 so that the exposed surface of the room may be freely decorated or washed and there is no likelihood of the liquid medium generally used for the purpose coming in contact with the absorbent material. Moreover, by this construction there is provided a thoroughly fireproof structure, the membranes and supporting means being preferably of non-inflammable material, and the sound absorbent means being also of a generally non-inflammable or fire resistant character.

I would state in conclusion that while the illustrated examples constitute practical embodiments of my invention, I do not wish to limit myself precisely to these details, since manifestly, the same may be considerably varied without departing from the spirit of the invention as defined in the appended claims.

Having thus described my invention, I claim as new and desire to secure by Letters Patent:

1. In building construction, spaced parallel supports, membrane units forming a surface adjacent said supports, said membranes having upstanding flanges at the edges forming sides, clips for attaching said membranes to said supports, and offset portions in said sides, said offset portions having slots formed therein for insertion of said clips.

2. In combination with a metallic membrane having upstanding flanges provided with slotted offsets, a clip for attaching said membrane to a building support, said clip comprising means for frictionally engaging said support, and substantially U-shaped means for engaging around an offset in a flange of said membrane.

3. In combination with a membrane for building construction, said membrane having an upstanding side provided with a longitudinal offset, a resilient clip comprising means for frictionally engaging with a building support, a substantially U-shaped portion engaging around said offset, and the lowermost leg of said U-shaped portion being bent downwardly to contact the base of said membrane to retain said clip in clipping position.

4. A membrane unit for building construction, comprising a planular blank, upstanding flanges on the edges of said blank, and a plurality of slotted offsets in opposite flanges to receive separable clip means for securing said membrane to a support.

5. A membrane unit for building construction, comprising a planular blank, the edges of said blank being bent upwardly in two sections, one of said sections being at an obtuse angle to said blank and the other section being substantially perpendicular to said blank, said sections forming beveled sides on said membrane, and slotted offsets in said perpendicular section adapted to receive clips for securing said membrane to a support.

6. A building construction of the character indicated, comprising a pair of spaced furring strips, each having a laterally extending outwardly facing surface, and an abutment surface which faces

in substantially the opposite direction, an acoustical tile formed as a foraminated pan having marginal flanges at opposite ends extending substantially perpendicularly to the plane of the main area with their edges abutting said outwardly facing surfaces of the respective furring strips, and extending longitudinally thereof in contact therewith, and means for securing said pan to the furring strips, including supporting 10 clips connected to the marginal flanges of the pan and each having a part adapted to extend past the outwardly facing surfaces of the furring strip and engage said abutment surfaces.

7. In the construction defined in claim 6, the 15 free end of each clip being formed with an outward lug extending obliquely to the plane of the main area of said pan.

8. A building construction of the character indicated, comprising a pair of spaced furring strips, 20 an acoustical tile formed as a foraminated pan having marginal inturned flanges at opposite ends, said flanges being incised and having a portion depressed inwardly to form a strap or loop, and spring clips for securing the pan to the furring strips each including a leg portion adapted 25 to be entered through one of said straps with its extreme end engaging the inner wall of the pan, and with an intermediate portion overlapping the upper edge of the flange, the other end of said 30 clip being shaped to yieldingly engage a co-operatively formed abutment surface of the furring strip.

9. In a building construction, a building surface, 35 hanger means connected with said surface, rails supported by said hanger means, perforated, metallic membranes forming the exposed surface of said construction, said membranes being provided with offset straps in spaced, parallel relation thereto, and clips secured by said straps to 40 said membranes for snapping said membranes into place adjacent said rails.

10. A building construction of the character indicated, comprising a plurality of parallel, 45 spaced furring strips, acoustical tiles formed as foraminated pans having marginal flanges extending laterally with respect to the plane of the main area, said pans being disposed with their flanges adjacent the longitudinal centers of the furring strips, and means for securing the 50 pans to the furring strips consisting of detachable supporting clips each having a portion extending through an aperture in the flange, with a portion overlying the outer surface of said flange, said flange adjacent the aperture being 55 depressed to accommodate the overlapping portion of the clip, and said clips each having a portion adapted to firmly engage a co-operatively formed abutment of the furring strip.

11. A building construction of the character 60 indicated comprising a pair of spaced furring strips, an acoustical tile formed as a foraminated pan having marginal flanges extending laterally from the plane of the main central area, and means for securing the tile to the furring strips, 65 including supporting clips detachably connected to said flanges and having portions adapted to engage cooperatively formed abutments of the furring strips, said clips each having a depend-

ing portion adapted to engage the flange of the pan for detachably holding the clip in place.

12. A building construction of the character indicated, comprising a plurality of parallel, 5 spaced furring strips, acoustical tiles formed as foraminated pans having marginal flanges extending laterally with respect to the plane of the main area, said pans being disposed with their flanges adjacent the longitudinal centers of the furring strips, the flange of said pan adjacent the furring strip having a portion offset to form a strap or loop, and means for securing the pans to the furring strips including supporting clips 10 formed of flat metal stock, each having a leg portion adapted to be extended through the strap of the pan, and each having a portion adapted when said leg portion is entered in the strap to engage the strap for holding the clip in position, said clips having portions opposite the leg adapted to engage co-operatively formed 15 abutments of the furring strips.

13. A building construction of the character indicated, comprising a pair of spaced furring strips having substantially flat outer surfaces, 20 an acoustical tile formed as a foraminated pan having marginal flanges at opposite ends, extending substantially perpendicularly to the plane of the main area, and means for securing the pan to the furring strips with the edge of each 25 of said flanges disposed in close proximity to said flat surface of the furring strip, said means consisting of supporting clips detachably connected to the flanges and each having an intermediate portion overlapping the edge of the flange and an outer portion formed to engage 30 an abutment surface of the furring strip, the outer edge of the flange being arranged to accommodate said intermediate portion of the 35 clip in a position substantially flush with said edge of the flange.

14. A building construction of the character indicated, comprising a pair of spaced furring strips, an acoustical tile formed as a foraminated pan having marginal inturned flanges at opposite ends, said flanges each having an offset portion 45 to form a strap or loop, and means for securing the pan to the furring strips, including spring 50 clips each having a leg portion adapted to be entered in one of said straps and an intermediate portion overlapping and seated in said offset, the other end of each clip being formed to yieldingly embrace the lower contour of the furring strip.

15. A building construction of the character indicated, comprising a pair of spaced furring strips, an acoustical tile formed as a foraminated pan having marginal inturned flanges at opposite ends, said flanges being incised and having 55 portions depressed to form straps or loops, and spring clips for securing the pan to the furring 60 strips, said clips each having one end bent upon itself in spaced-apart relation for entry in the strap, the extreme tip of said end portion being provided with a portion engaging the pan for holding the clips in position, the other ends of 65 the clips being formed to engage an abutment shoulder of the furring strip.

CARL S. STROM.
